(57) **CLAIM**

The ornamental design for a skincare mask with charger, as shown and described.

DESCRIPTION

FIG. 1 is a front perspective view of the skincare mask in use in accordance with the present design;

FIG. 2 is a back perspective view of the skincare mask in use in accordance with the present design;

FIG. 3 is a front view of the skincare mask in use in accordance with the present design;

FIG. 4 is a back view of the skincare mask in use in accordance with the present design;

FIG. 5 is a left view of the skincare mask in use in accordance with the present design;

FIG. 6 is a right view of the skincare mask in use in accordance with the present design;

FIG. 7 is a top view of the skincare mask in use in accordance with the present design;

FIG. 8 is a bottom view of the skincare mask in use in accordance with the present design;

FIG. 9 is a front perspective view of the skincare mask on a charger in accordance with the present design;

FIG. 10 is a back perspective view of the skincare mask on the charger in accordance with the present design;

FIG. 11 is a front view of the skincare mask on the charger in accordance with the present design;

FIG. 12 is a back view of the skincare mask on the charger in accordance with the present design;

FIG. 13 is a left view of the skincare mask on the charger in accordance with the present design;

FIG. 14 is a right view of the skincare mask on the charger in accordance with the present design;

FIG. 15 is a top view of the skincare mask on the charger in accordance with the present design; and,

FIG. 16 is a bottom view of the skincare mask on the charger in accordance with the present design.

The dashed broken lines throughout the drawing figures depict portions of skincare mask with charger that form no part of the claimed design.

1 Claim, 16 Drawing Sheets
